UNITED STATES PATENT OFFICE.

ALFRED H. SANDER, OF MAPLEWOOD, NEW JERSEY, ASSIGNOR TO GEORGE BORGFELDT & CO., OF NEW YORK, N. Y., A CORPORATION OF NEW JERSEY.

DESIGN FOR A COFFEE PERCOLATOR, TEAPOT, OR SIMILAR ARTICLE.

Application filed September 10, 1921. Serial No. 499,829. Term of patent 3½ years.

To all whom it may concern:

Be it known that I, ALFRED H. SANDER, a citizen of the United States, residing at No. 92 Roland Avenue, in the village of Maplewood, county of Union, and State of New Jersey, have invented a new, original, and ornamental Design for a Coffee Percolator, Teapot, or Similar Article, of which the following is a specification, reference being had to the accompanying drawing, forming a part thereof.

The figure shown in the drawing is a side view of a coffee percolator embodying my design.

It is to be understood that my claim includes all substantial equivalents of my design as shown and described.

I claim:

The ornamental design for a coffee percolator, teapot or similar article, substantially as shown and described.

ALFRED H. SANDER.
